UNITED STATES PATENT OFFICE.

CREIGHTON C. WEST, OF WYOMING, NEBRASKA.

GRAPPLING TOOL.

Application filed October 25, 1921. Serial No. 510,201.

To all whom it may concern:

Be it known that I, CREIGHTON C. WEST, a citizen of the United States, residing at Wyoming, in the county of Otoe and State of Nebraska, have invented certain new and useful Improvements in Grappling Tools, of which the following is a specification.

This invention relates to a tool for removing objects from wells and the like, the principal object of the invention being to provide a pair of jaw members for gripping the object, with means for causing the jaws to engage the object when a releasing member is moved by the object to a position where it will permit the jaws to close.

Another object of the invention is to provide spring means for securing the releasing member to the body of the device, so that said member may be placed in a position holding the jaws apart or in a position away from the jaws which will permit them to close on the object.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a longitudinal sectional view showing the invention in use.

Figure 2 is a similar view showing the jaws as engaging the object.

Figure 3 is an enlarged sectional view of the lower ends of the jaws with the spreading member in position.

Figure 4 is a section on line 4—4 of Figure 3.

Figure 5 is a view showing a modified form of spreading member.

Figure 6 is a view showing another form of spreading member.

In these figures 1 indicates a stem which is adapted to be connected with piping or a cable in order that it may be lowered into a well. A pair of jaws 2 are connected to the lower end of this stem, these jaws being shown as metal strips with their upper ends riveted or bolted to the stem and their lower

ends being rounded and flanged to form opposing jaw faces 2'. These jaws are adapted to be held in spreaded condition by a member 3, which is shown in Figures 1 to 4 as being in the form of a pin, the eye of which is engaged by the lower end of a flexible member 4, the upper end of which is connected to a spring 5 which in turn is connected to a staple at the lower end of the stem by a flexible member 6. This spring will permit the member 3 to be placed between the lower ends of the jaws to spread said jaws apart and in this position the spring will be in expanded form so that if the spreading member is struck, as by the object to be removed from the well, the spring will jerk said member upwardly from between the jaws and said jaws will thus come together and grip the object, so that it can be removed from the well with the device.

The pin is placed in position spreading the jaws apart, before the device is lowered in the well.

Figure 5 shows a pin having a screw threaded socket to receive a bolt 7 so that the pin is adjustable as to length. This pin can be used to make the device fit varying sizes of wells.

Figure 6 shows another form of spreading device. This view shows a pair of members 8 connected together at their abutting ends by the connecting means and having the well known toggle lever effect. When this device is engaged by the object the members will move together and then they will be jerked upwardly by the spring.

While this device can be used for removing objects from all kinds of wells it is especially designed to raise loose valves from "Red jacket" pumps as shown in the drawings.

It is thought from the foregoing description that the advantages and novel features of my invention will be readily apparent.

I desire it to be understood that I may make changes in the combination and arrangement of the several parts, provided that such changes fall within the scope of the appended claims.

What I claim is:—

1. A device of the class described comprising a stem, jaws carried thereby, a spreading member for the jaws adapted to

be moved from between the jaws by an object in the well and spring means for moving the member into inoperative position.

2. A device of the class described comprising a stem, spring strips connected with the same for forming a pair of jaws, a pin for spreading the jaws apart and a spring connecting the pin with the stem.

3. A device of the class described comprising a stem, spring strips connected with the stem and forming jaws, a member for holding the jaws apart, means for adjusting the member and spring means for connecting the member with a part of the stem.

In testimony whereof I affix my signature.

CREIGHTON C. WEST.
